UNITED STATES PATENT OFFICE.

WALTER SODERLING, OF NEW YORK, N. Y.

RESPIRATOR.

1,317,947.

Specification of Letters Patent. Patented Oct. 7, 1919.

Application filed November 17, 1917. Serial No. 202,468.

To all whom it may concern:

Be it known that I, WALTER SODERLING, a citizen of the United States, and a resident of the borough of Manhattan, city, county, 5 and State of New York, have invented an Improvement in Respirators, of which the following is a specification.

This invention relates to respirators and more particularly to that type of respirator 10 adapted for use in filtering air laden with dust or other particles.

Among the objects of this invention may be mentioned the provision of a simple, practical and durable respirator of highly 15 efficient action, and of relatively inexpensive construction. Another object is to provide a respirator of minimum size and weight and of such flexibility of construction, that any or all parts are readily and conveniently taken apart for inspection, cleaning, 20 replacement or repair of the parts. This invention aims also to provide a rigid and durable filter mounting or retainer in which the filter medium is securely mounted for 25 most efficient action, and of such character that the medium may be readily and conveniently replaced or renewed. Among the objects also may be pointed out to provide a respirator adapted to be applied to the 30 face and having such novel features as to insure maximum comfort to the wearer under all conditions of use. Another object is to provide a simple and practical construction to minimize the exposure of metal 35 parts to the moisture inside the device and thus to decrease the corrosive action thereon.

In the accompanying drawing, in which is shown one of various possible embodiments of this invention, and in which similar reference characters refer to similar parts,

Figure 1 is a perspective view showing the respirator in use as applied to the face of the wearer.

Fig. 2 is a front elevation of the assembled respirator with certain parts broken away to show the construction more clearly, and

Fig. 3 is a side elevation of the same.

Fig. 4 is a central cross section of the respirator, and

Figs. 5 and 6 are partial cross sections of the respirator body to show the construction and action thereof more clearly.

Figs. 7 and 8 are rear views of the respirator body portion, illustrating certain features, and

Fig. 9 is a partial cross section showing a modified form of filter mounting and showing certain features of the invention.

Referring now to the drawings there is shown a respirator comprising a body portion 10 upon which is mounted, by means to be hereinafter described, an air transmitting medium or filter retainer 28. The respirator with the parts in assembled relation, as shown in the drawings, may be applied to the face and held in operative position thereon by means of the straps 12 and 13 secured to the body portion 10 by means of 70 the double-headed buttons 14 and 15 fastened in suitable openings in the body 10, and passing around to the back of the neck where they are hooked together by suitable means, such as the hook 16 and the eye 17. 75 The straps are preferably of an elastic construction, and in order that the pressure with which the respirator is held in contact with the face may be varied at will, the tension of the elastic straps may be adjusted 80 by means of the buckle 18.

The body portion 10 is composed of a relatively flexible material, preferably rubber, and is made of such size and shape as to closely incase the nose and mouth of the 85 wearer, so that the air space surrounding these parts is a minimum. Accordingly, the innermost end or face-contacting end of the body 10 is made of sufficient size to encompass the nose and mouth of the wearer and the body 10 is then gradually diminished in cross section to terminate at its outermost end preferably in a ring 19, provided at its outer surface with a bead 20. Upon this ring, and held in position by the bead 20, is 90 mounted the filter retainer in a manner to be hereinafter described.

Referring to Fig. 4, it will be seen that the thickness of the material forming the body 10 is gradually reduced as it approaches the face-contacting portion thereof. This material, being preferably of rubber and being relatively flexible, is made at the outermost end of the body 10, as for example in the portions adjacent the ring 19, 100 of a thickness sufficient to insure the proper rigidity of the structure. The material composing the body 10 immediately adja-

cent the face-contacting edge 21 is gradually reduced in thickness, as is more clearly shown in Fig. 5, to produce a circumferential face-contacting portion having a 5 gradually tapering or feather edge. This reduction in thickness of the portion of the body 10 adjacent the face results in the production of a thin face-contacting edge of great resiliency and flexibility, by which 10 material advantages are gained, as will be pointed out hereinafter.

The body 10 is provided on the two sides of the uppermost or nose-incasing portion with knobs 22-23 respectively, which may 15 be made integral with the body 10. Secured in suitable openings in the knobs 22-23 is a substantially V-shaped wire 24 preferably of a steel composition. The ends of this wire pass through the knobs 22-23 and 20 may be bent over as is more clearly shown in Fig. 3.

The mounting for the filter comprises a ring-shaped sheet metal member 25 provided with a cylindrical portion 26, and an 25 annular end portion 27 adapted to engage the ring 19 and to be held in place thereon by the bead 20, as is shown in cross-section in Fig. 4. The circular opening in the end portion 27 is made substantially of the same 30 diameter as the outside diameter of the ring 19, immediately adjacent the bead 20. The body 10, being of a relatively flexible material, is readily collapsed or folded in at its reduced or attenuated portion and passed 35 through the opening of the end portion 27. Upon the return to normal of the ring portion of body 10, the ring member 27 will be securely mounted upon the ring 19 and rigidly held in position by the bead 20 at 40 the same time forming a substantially airtight joint therewith.

The filter 28 is preferably circular in form, and is mounted upon the cylindrical portion 26 of the ring-shaped member 25 by 45 means of a fastening member 29. The fastening member is substantially ring-shaped and comprises a cylindrical or band portion 30 adapted to fit over the cylindrical portion 26 and the superposed filter thus securely 50 retaining the latter in operative position. In order to insure great rigidity to the ring member 29, a bead 31 is provided at the outer end of the cylindrical portion 30. The bead 31 terminates at its outer end in an annular end portion 32 which extends outwardly as shown in Fig. 4 to insure the 55 rigidity and strength of the fastening member 29. In order, however, not to decrease the exposed area of the filtering member 28 and therefore its effectiveness of operation, the annular end portion 32 is gradually curved outwardly and away from the medium 28 as is clearly shown in cross section 60 in Fig. 4. By reason of such construction 65 of the fastening member 29, maximum rig-

idity of the filter mounting is attained without impairment of the efficiency of operation of the filtering medium 28.

The parts 25-29 of the mounting are preferably of a metal, for example aluminum, which is not readily susceptible to corrosion or oxidation, and it will be noted that the construction herein described provides for a minimum interior exposure of such parts to the moisture contained in the exhaled air. Corrosive action is thus brought 75 to a minimum and the life of the parts greatly prolonged.

In the use of this respirator a suitable air filtering medium is secured to the mounting 80 in the manner heretofore described and the respirator applied to the face, incasing the nose and the mouth, and is held in place by means of the straps 12-13. The filtering medium may be of various types, according 85 to the use to which the respirator is put. In the embodiment herein shown, this medium is a dry filter adapted to be used in atmospheres laden with dust and other particles, and is preferably provided with a 90 substantially smooth exterior surface. In this manner the dust and other particles, prevented from passing through the medium upon an inhalation, are caught upon the exterior surface thereof and, upon the succeeding exhalation of air, are blown off, leaving the pores of the medium free and unobstructed. Breathing is thereby facilitated with least inconvenience and with minimum effort. It is to be noted, however, that 95 this medium may be chemically treated and otherwise modified to adapt it to be used for purifying gas-laden atmospheres by chemically or otherwise neutralizing the obnoxious gases therein.

It is further to be noted that the construction is such that the respirator closely incases the nose and mouth. In this manner the air space is made a minimum and the amount of dead air remaining within 100 the respirator is reduced to a minimum. This construction insures the inhaling of a maximum amount of fresh or purified air drawn directly through the filter by diminishing the amount of dead air remaining 105 within the respirator.

Upon being applied to the face, the face-contacting portions of the respirator, which as previously described terminate in a gradually tapering edge, contact with the face 110 substantially as shown in Fig. 5, the contact being practically a line of contact. Upon adjusting the tension of the straps 12-13, by means of the buckle 18, so that the respirator will be securely held against 115 the face, the contacting portions of the body 10 will take, in general, the form shown in cross-section in Fig. 6. The edge portions of the body 10, being gradually tapered, have a greater degree of flexibility and resil- 120

130

iency than the body portion proper and are readily curved outwardly as in Fig. 6, due to the pressure applied to the respirator by the straps. The contact with the face there-
5 upon becomes a peripheral surface of contact, as will be obvious from Fig. 6, and by rea-
son of the great flexibility and resiliency of the face-contacting portions of the body 10, these portions readily conform to the ir-
10 regularities of the contour of the face, without impairing the surface of contact there-
with or the air-tightness thereof. The action of the face-contacting portions as just described, results in the production of a con-
15 tact with the face, the air-tightness of which is greater and more reliable than if the contact were not distributed over a surface. The degree of air-tightness is a function of the area of the surface of contact, the greater
20 the surface the greater the air-tightness. By increasing the pressure by which the respirator is held in contact with the face, the surface of contact can be increased in area, as will be obvious from Fig. 6, and the
25 air-tightness correspondingly increased. The pressure may be adjusted by varying the tension exerted by the straps 12—13, whence the surface of contact is correspondingly adjusted.
30 The action of the face-contacting edge of the respirator body will be as hereinbefore described and substantially uniform throughout the entire periphery, excepting in the parts of the periphery on either side
35 of the nose which contact with the face in the depression adjacent the nose and the eye. In order to maintain substantial uniformity of action throughout of the edge portions to contact with the face in a sur-
40 face, the wire attachment 24 provides for adjusting the body portion 10 to insure proper action of the tapered edge. This at-
tachment, in the embodiment herein shown, comprises the steel wire 24 which, when
45 manually adjusted and set, adjusts the width of the body portion 10 to accommodate it to noses of various widths, thereby to so position the edge portions thereof with re-
spect to the depressions adjacent the nose,
50 as to cause the contacting edge to assume the proper form, to contact in a surface. This adjustment may be so made that the proper surface of contact with such depre-
sions is attained even before pressure is ap-
55 plied to the body proper. In this manner the part of the body portion 10 immediately surrounding the nose may be given any de-
sired degree of contraction commensurate with the degree of contact desired at these
60 parts. It will be obvious that means may be used other than the wire 24 for varying the contraction of the body portion 10.
65 The construction of a gradually tapered face-contacting edge, acting as described to contact with the face in a surface through-

out its entire periphery, results in a sub-
stantially air-tight contact with the face and at the same time insures a maximum degree
of comfort to the wearer. Aside from pro-
ducing an air-tight contact, the feather edge
70 portions engaging the face in a resilient sur-
face produce a soft and non-irritant con-
tact with the face and avoid a high and
uncomfortable intensity of pressure upon
the face by reason of the distribution of the
75 pressure throughout a surface. Furthermore,
constant irritation and sores and other
discomforts are effectually done away with
by the yielding or resilient engaging surface.

It has been found that respirators, partic-
ularly when used in atmospheres of low tem-
perature, are affected by the condensation of
the moisture in the exhaled air upon the in-
terior walls of the respirator body. In cold
atmospheres this condensation and resultant
80 accumulation of moisture, may be consider-
able, and result in much discomfort to the
wearer.

In order to effectively prevent such ob-
jectionable accumulation, a lining 33, as
85 shown in Fig. 7, is provided for the interior
of the respirator body 10. This lining may
be constructed of a suitable cotton or flannel
material, and is so shaped as to substantially
cover the interior surface, leaving the pe-
90 riphery or face-contacting edge free to func-
tion in the manner heretofore described.
The lining 33 overlaps at its ends 38, which
are suitably sewed together and is prefer-
ably secured to the body 10 by means of the
95 buttons 14 and 15, which likewise serve to
attach the fastening straps 12 and 13 respec-
tively to the respirator body. It is to be un-
derstood, however, that this invention also
contemplates securing the lining in other
100 of various possible manners. In Fig. 7 the
lining 33 is shown encompassing the in-
terior surface excepting that portion there-
of immediately adjacent the nose. This con-
struction is not undesirable, since the maxi-
105 mum amount of condensation occurs in the
major portion of the respirator which is
therefore lined as shown in Fig. 7. It is
to be understood, however, that this lining
may cover the entire interior surface, as in-
110 dicated by the broken line 37.

The lining 33 serves to interpose a non-
heat-conducting medium between the body
portion 10 and the moisture-laden atmos-
phere contained therein. The latter is there-
120 by maintained out of direct contact with
the cold body 10 and condensation with re-
sultant collection of moisture is thereby im-
mediately reduced. Whatever slight con-
densation takes place is immediately ab-
sorbed by the lining 33 so that the disadvan-
tages resulting from condensation of mois-
ture are effectively removed. The lining 33
is readily removable and may be replaced
without inconvenience and without detract-
125

130

ing from the sanitary features of the respirator as a whole.

It has also been found that the accumulation of moisture resulting from condensation or from perspiration in the peripheral parts contacting with the face, works out from beneath the edge and gathers dust particles which result in great irritation when such conditions exist in atmospheres laden with chemical dusts which readily react with water, such as lime dust for example. In order to prevent such working out of the moisture and chemical reactions with their resultant effects on the skin, the lining may be extended over and beyond the face-contacting edge of the respirator as shown in Fig. 8. The lining 34 is here shown extended beyond the edge of the lower face-contacting portion of the body 10, but it may be pointed out here that this invention contemplates also the provision of a lining extending beyond the edge throughout the entire peripheral face-contacting portions of the body, as is clearly indicated by the broken line 39 in Fig. 8. As shown in Fig. 8, this extension is combined with the lining heretofore described for preventing the condensation of the moisture on the interior surface of the respirator body, and is likewise made readily detachable by fastening to the buttons 14 and 15.

The lining 34 serves to insulate the contact with the face from the moisture resulting from condensation or perspiration, by effectively absorbing the moisture within itself. In this manner a contact with the face is produced which is free from moisture and hence does not produce disagreeable irritations resulting from chemical reactions of the dusts with free moisture. The lining 34 is likewise readily detached and replaced whenever sanitary conditions require, and at no time interferes with the functioning of the feather face-contacting edge as heretofore described in detail.

In Fig. 9 is shown a modified form of respirator, comprising the improved body portion 10 terminating in a ring 19 provided at its outer surface with a bead 20 as heretofore described. The filter mounting is provided with a ring-shaped sheet metal member having a flared annular end portion 27' terminating at its outer end in the cylindrical portion 26'. At its innermost end and smaller diameter, the sheet metal member is provided with an annular flanged portion 35, so formed as to receive and substantially incase the bead 20 on the ring 19 of the body portion 10. This construction results in a mounting, the inner surface of which is substantially continuous and unbroken, the end face of the ring 19 and bead 20 substantially merging into the flaring surface of the portion 27'. The filter medium 28' is mounted upon the cylindrical end portion

26' by means of the fastening member 29' in the manner heretofore described.

In order to diminish the exposure of the metal parts to the moisture-laden exhaled air, the annular washer 36 is provided and adapted to fit into the ring-shaped member 26' to substantially cover the interior surfaces thereof. This washer is preferably made of a felt material, and its outside diameter is made slightly larger than the inside diameter of the cylindrical portion 26'. The diameter of the opening in the washer 36 is made substantially equivalent to that of the opening in the ring portion 19 of the body 10. The washer 36, being of a greater diameter than that of the cylindrical portion 26', will assume a position and form, when inserted in the filter mounting, substantially as shown in Fig. 9, and will conform to the flaring annular end portion 27'. The opening in the washer will register with the opening in the body 10, and will form substantially a continuation thereof.

It will be noted that the washer 36 effectively covers the surface of the metal parts of the filter mounting which are exposed to the moisture in the vitiated air. In this manner the effects of rusting and corrosion, due to the presence of moisture are effectively eliminated, and the life of the filter mounting prolonged. It is to be noted that the washer 36 is not confined in its application to the modification shown in Fig. 9, and that it is readily adaptable to other constructions, such as is shown in Fig. 4, for example.

It will be seen that this invention provides a simple and practical respirator of light weight and of relatively inexpensive construction. It is noted also that there is provided a respirator of great convenience and of a minimum discomfort to the wearer, and that it is of such construction as to leave a free and unobstructed line of vision. These features combine to allow the use of goggles or glasses with this respirator without combining such goggles therewith to form a cumbersome mask.

It may be set forth also that this invention provides a respirator that may be readily adapted to various conditions of use, such as in dust or gas-laden atmosphere, in connection with surgical work, and others.

It is also to be pointed out that a respirator is provided which is readily taken apart and reassembled and that therefore the parts may be readily replaced. This is particularly true of the filter medium which may have to be frequently renewed. Furthermore, the construction provided for allows the respirator to be readily taken apart for inspection, cleaning or sterilization. In the latter case sterilization is completely accomplished since each part of the respirator is readily operated upon individually.

This invention also provides, it will be noted, a filter mounting of great simplicity and of great durability, combining great strength, rigidity and simplicity without impairment of efficient action of the filtering medium itself.

As various possible embodiments might be made of the above invention and as various changes might be made in the embodiment above set forth, it is to be understood that all matter herein set forth or shown in the accompanying drawings is to be interpreted as illustrative and not in a limiting sense.

15 I claim as my invention:

1. A respirator comprising a face engaging member of flexible molded material and spring means located outside of said face engaging member and engaging spaced portions of said member and adapted to press said portions yieldingly toward each other to effect conforming contact of said member with the nose and face of the wearer.

2. A respirator comprising a face engaging member having U-shaped spring means attachable externally and adjustable to retain said member yieldingly in face conforming shape.

3. A respirator comprising filter retaining means, a face engaging member having a face engaging attenuated edge, and a laterally yielding U-shaped spring engaging the face engaging member at a less attenuated portion to hold the attenuated edge in conforming contact with the nose and face of the wearer.

4. A respirator comprising filter retaining means including a filter supporting ring, and a face engaging member having a relatively rigid ring supporting portion provided with 40 means to prevent accidental detachment of said ring from said rigid portion in a forward direction and a relatively flexible and resilient portion normally larger than the opening in said ring but adapted to be 45 yieldingly distorted and passed through said opening to engage the ring on the relatively rigid portion of said face engaging member and when in normal distended condition of use to prevent accidental detachment of the ring in a rearward direction. 50

5. A respirator comprising a face engaging member of flexible material, a filter supported in effective air filtering relation to said face engaging member, and spring 55 means located outside of said face engaging member and engaging spaced portions of said member and adapted to press said portions yieldingly toward each other to effect conforming contact of said member with 60 the nose and face of the wearer.

6. A respirator comprising a face engaging member having U-shaped spring means attachable externally and adapted to retain said member yieldingly in face conforming 65 shape and a filtering member arranged in effective air filtering relation with respect to said face engaging member.

In testimony whereof I have signed my name to this specification this 15th day of 70 November, 1917.

WALTER SODERLING.
